UNITED STATES PATENT OFFICE

125,127

DESIGN FOR A PUZZLE

George Clift, Detroit, Mich.

Application March 11, 1940, Serial No. 90,826

Term of patent 7 years

To all whom it may concern:

Be it known that I, George Clift, a citizen of the United States, residing at Detroit, in the county of Wayne and State of Michigan, have invented a new, original, and ornamental Design for a Puzzle, of which the following is a specification, reference being had to the accompanying drawing, forming part thereof. The article, except for the cords uniting the two pieces of the

puzzle, is made of sheet metal and has no appreciable thickness.

The figure is a side elevational view of a puzzle showing my new design.

I claim:

The ornamental design for a puzzle, as shown and described.

GEORGE CLIFT.
